UNITED STATES PATENT OFFICE.

LOUIS COHEN AND JOSEPH O. MAUBORGNE, OF WASHINGTON, DISTRICT OF COLUMBIA.

ELECTRICAL SIGNALING.

Application filed June 16, 1920. Serial No. 389,451.

To all whom it may concern:

Be it known that we, LOUIS COHEN and JOSEPH O. MAUBORGNE, citizens of the United States, residing in Washington, in 5 the District of Columbia, have invented certain new and useful Improvements in Electrical Signaling, of which the following is a specification.

This invention relates to the art of radio 10 signaling, and particularly receiving radio signals, and a system for use in practicing the same.

The object of the present invention is an improvement in the method and apparatus 15 for the reception of radio signals, securing thereby better tuning, reducing interference effects, and effecting a simplification in the equipment required.

In the present practice of the art tuning 20 is accomplished by the use of inductance coils and condensers so adjusted as to be in resonance for the frequency of the signals to be received. To obtain sharp tuning so as to reduce interference from foreign signals to a minimum, a complicated network 25 of circuits is usually required making it relatively expensive and difficult to handle in the matter of adjustments.

In this invention the tuning is accomplished by the use of a resonance wave coil 20 on which a wave development is produced by the incoming signals, and the detector connection adjusted to the point of the loop of potential, or the loop of current of the 35 wave developed on the coil, depending on the type of connection used. The resonance wave coil is preferably made in the form of a long helix, all the electrical constants of which, inductance, capacity and resistance, 40 are of a distributed character. The coil is wound with a large number of turns of insulated wire per unit length, and the winding may be either single layer or multiple layer, the object being to secure large inductance per unit length so as to get in a comparatively short length the equivalent condition of a long line in the matter of wave development. The wave length adjustment for different signal frequencies is 45 accomplished by either varying the length of the coil or by changing one of the electrical constants, preferably the capacity, of the coil, so that in either case the natural wave length of the antenna system would 50 correspond to the wave length of the signals desired to receive.

The resonance wave coil may be used either with or without an antenna. In the latter case the coil functions as the antenna as well as the tuning element, the coil by itself constituting the complete receiving equipment.

The principle of operation and the method of using our invention can be better understood by a reference to the accompanying diagrammatic figures which show typical embodiments of the invention and form part of this specification.

In the accompanying drawings:

Figure 1 is a diagrammatic view of a system for carrying out the invention in which the natural wave length of the antenna and wave coil system is varied by moving a grounded metal tube over the wave coil;

Figure 2 is similar to Figure 1, showing 75 the detector connected to a point on the coil and to ground;

Figure 3 is a diagrammatic view of an arrangement for carrying out our invention in which the natural wave length of the antenna and wave coil system is varied by shifting the ground connection on the wave coil;

Figure 4 shows another embodiment of 80 our invention in which coupled circuits are employed, in each of which a resonance wave coil is used.

Figure 5 is a schematic view showing an untuned coupled circuit;

Figure 6 shows an arrangement in which 90 the variation of the electrical constants of the wave coil is obtained by moving a grounded metal tube inside the coil; and,

Figure 7 shows still another modification 95 of our invention in which no antenna is used; the wave coil with a grounded metal tube sliding over it constituting the complete antenna system.

Having more particular reference to the drawings, and in connection with which like 100 characters of reference will designate corresponding parts throughout, in Figure 1 the antenna (1) is connected directly to the resonance wave coil (2), and a metal tube (3) which is grounded at (4) slides over 105 the coil (2) and is insulated from it. (5) designates a metal plate or narrow metal ring moving along the coil axially and is connected by wire (8) to the detector (6), at the point (7). The capacity per unit 110 length of that part of the coil which is inclosed in the tube is much greater than the

part of the coil outside the tube. The natural wave length of the coil as a whole would therefore depend on the relative lengths of the parts of the coil which are in the metal tube and outside of it. By moving the metal tube (3) along the coil (2) so as to inclose a greater or smaller part of it, the natural wave length of the coil is altered; also the position of the tube on the coil, that is, whether at the end of the coil or at the middle part of the coil would have an effect on the capacity distribution of the coil and consequently affect the natural wave length of the coil. This evidently affords a means of adjusting the wave length of the antenna and wave coil system so as to bring it into resonance with the wave length of the signals desired to receive. The metal plate (5) serves as an electrostatic connection between the coil (2) and the detector (6). The plate (5) is adjusted along the axis of the coil for the point of the loop of potential for maximum sensitivity. In this arrangement a unilateral connection to the detector is shown. (6) designates the electron tube amplifier and detector, and (7) is the input grid terminal of said amplifier.

According to Figure 2 the detector (6) is connected directly to a point (5') on the wave coil (2), the connecting point being adjustable along the coil; the other terminal of the detector (9), which in the case of an electron tube is a filament, connected at (10) and by lead (11) to the ground (4). The principle of operation is similar to that described for Figure 1.

Another embodiment of the invention is shown in Figure 3. The natural wave length of antenna and wave coil system is changed by varying the amount of the coil included in the antenna circuit 1, 2, 10, 11 and 4, which is accomplished by moving the connection (10) along the coil.

In Figure 4 a coupled circuit arrangement is shown in which the antenna circuit 1, 2, 3, 10 and 4 and the secondary circuit 16, 2', 3', 10', and 4' are separately tuned by a resonance wave coil, in the manner described in connection with Figure 1. In both circuits a grounded metal tube slides over the resonance wave coil, thereby adjusting the natural wave length of each system to correspond to the wave length of the incoming

signals to be received. The secondary (16) is movable so as to couple to different parts of the coil (2) of the antenna circuit.

According to Figure 5 an untuned secondary (16) is used to couple the detector (6) to the antenna circuit, the secondary (16) is movable along the axis of the coil (2) and may be connected to one terminal of the detector, the grid connection, in case of an electron tube detector, leaving the other terminal open, or the two terminals connected to (7) and (9), the grid and filament respectively of an electron tube detector, as shown in the figure.

Figure 6 is similar to Figure 1 except that a variation of the electrical constants of the resonance wave coil to produce a change in the natural wave length of the antenna and wave coil system is accomplished by placing a grounded metal tube (3) inside the coil and effecting a change in the electrical constants of the coil by moving the metal tube in or out of the coil, the method and principle of operation being the same as that described for Figure 1.

In Figure 7, an arrangement is shown for receiving radio signals in which the resonance wave coil (2) serves as the antenna for picking up the energy of the incoming signals, as well as being the tuning element. In this case also the tuning is accomplished by shifting the metal tube (3) along the axis of the coil (2) thus varying the natural wave length of the coil.

We claim:

1. A system of receiving radio signals comprising an antenna, a resonance wave coil, an adjustable grounded metal tube operatively associated with said resonance wave coil, a secondary circuit coupled to said resonance wave coil, and an indicating device connected to said secondary circuit.

2. A system of receiving radio signals comprising an antenna, a resonance wave coil and an adjustable grounded metal tube sliding over said resonance wave coil, a secondary circuit, and a resonance wave coil of variable wave length in said secondary circuit, said secondary circuit being coupled to the resonance wave coil of the antenna circuit.

J. O. MAUBORGNE.
